UNITED STATES PATENT OFFICE.

LUTHER W. HARWOOD, OF TROY, NEW YORK, ASSIGNOR TO FULLER, WARREN & CO., OF SAME PLACE.

DESIGN FOR A COOKING-RANGE.

Specification forming part of Design No. 5,448, dated December 26, 1871.

SPECIFICATION.

To all whom it may concern:

Be it known that I, LUTHER W. HARWOOD, of the city of Troy, in the county of Rensselaer and State of New York, have invented and produced a new and original Design for Cooking-Ranges or Stoves, of which the following is a specification, reference being had to the accompanying sheet of photographs, in which—

Figures 1 and 2 represent different views of a range having my said design.

Like letters indicate similar parts in both figures.

One part of my invention is the design for the front plate A and end plates B C, as distinguished by the row of ornamentalations d, shaped and arranged along the outwardly-curved upper portion of said plate or plates so as to appear substantially as represented in the aforesaid photographs.

Another part of my invention is the design for the compound ornamental-border molding E, as distinguished by the corrugated outer surface f, the inner row of pointed projections g, and the intermediate portion h, all shaped and arranged together so as to present substantially the same appearance as is shown in the aforesaid photographic representation.

Another part of my invention is the combination of the border-molding E and a pendent ornament or ornaments, I, with or without an intervening molding, J, all shaped and arranged together so as to appear substantially as shown in Fig. 1, all shaped and arranged together so as to appear substantially as shown in the aforesaid photographs.

Another part of my present invention is the design for the grate-shank door K, substantially as shown in the aforesaid representations.

Another part of my invention consists in the ornamentation of a plate of a stove or range by means of the words "Hot-Blast Range," composed of letters all shaped and arranged together in a curved line upon the plate, so as to appear substantially as represented in Fig. 2 of the photographs.

What I claim as my present invention is—

1. The design for the front plate A and end plates B C, as herein specified.
2. The design for the molding E, as described.
3. The combination of the border-molding E and pendent panel ornament or ornaments I, with or without an intervening molding, J, as herein set forth.
4. The design for the grate-shank door K, as described.
5. The words "Hot-Blast Range," composed of letters shaped and arranged together on a plate of a stove or range in the ornamental manner herein described.

LUTHER W. HARWOOD.
